US00D592278S

(12) **United States Design Patent**
Leber

(10) **Patent No.:** **US D592,278 S**
(45) **Date of Patent:** **** May 12, 2009**

(54) **SHOWERHEAD**

(75) Inventor: **Leland C. Leber**, Fort Collins, CO (US)

(73) Assignee: **Water Pik, Inc.**, Fort Collins, CO (US)

(**) Term: **14 Years**

(21) Appl. No.: **29/299,256**

(22) Filed: **Dec. 20, 2007**

(51) LOC (9) Cl. **23-01**

(52) U.S. Cl. **D23/229**

(58) **Field of Classification Search** **D23/223, D23/213, 226, 229-230; 239/394, 282-283**
See application file for complete search history.

(57) **CLAIM**

The ornamental design for a showerhead, as shown and described.

DESCRIPTION

FIG. 1 is a bottom perspective view of a showerhead with the broken lines showing nozzles and user-engagement features for illustrative purposes only and forming no part of the claimed invention;

FIG. 2 is a bottom view of the showerhead of FIG. 1, with the nozzles and user-engagement features not shown in this figure;

FIG. 3 is a back view of the showerhead of FIG. 1, with the user-engagement features not shown in this figure;

FIG. 4 is a top view of the showerhead of FIG. 1, with the user-engagement features not shown in this figure;

FIG. 5 is a right side view of the showerhead of FIG. 1, with the user-engagement features not shown in this figure; and, FIG. 6 is a left side view of the showerhead of FIG. 1, with the user-engagement features not shown in this figure.

The front view of the showerhead is a mirror image of the back view.
